UNITED STATES PATENT OFFICE

117,784

DESIGN FOR A TOY

Grace M. H. Dubbles, Lincoln, Nebr.

Application January 30, 1939, Serial No. 82,660

Term of patent 7 years

To all whom it may concern:

Be it known that I, Grace M. H. Dubbles, a citizen of the United States, residing at Lincoln, in the county of Lancaster and State of Nebraska, have invented a new, original, and ornamental Design for Toys, of which the following is a specification, reference being had to the accompanying drawing, forming part thereof.

I claim:

The ornamental design for a toy, as shown.

GRACE M. H. DUBBLES.
